RESTAURANT BOOTH SEAT

Robert H. Sand, Los Angeles, Calif., assignor to Elster's, Hollywood, Calif., a corporation of California

Filed Apr. 11, 1968, Ser. No. 11,421

Term of patent 14 years

Int. Cl. D6—01

U.S. Cl. D15—11

FIGURE 1 is a perspective view of a restaurant booth seat showing my design;

FIGURE 2 is a top plan view;

FIGURE 3 is a front view; and

FIGURE 4 is a right end view of the restaurant booth seat.

The dominant features of my design reside in those portions shown in full lines on the drawing.

I claim:

The ornamental design for a restaurant booth seat, as shown and described.
